CLAIM

The ornamental design for a tool storage rack as shown and described.

DESCRIPTION

FIG. 1 is a perspective view of a tool storage rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of the portion labeled "9" in FIG. 1; and,

FIG. 10 is an enlarged view of the portion labeled "10" in FIG. 2.

The broken lines depict portions of the tool storage rack that form no part of the claimed design. The dot dash broken lines illustrate the bounds of the enlarged views and form no part of the claimed design.

1 Claim, 10 Drawing Sheets
